DESIGN FOR A LAVATORY

George W. Kohlmeyer, Buffalo, N. Y., assignor to
W. A. Case & Son Manufacturing Company,
Buffalo, N. Y., a corporation of New York

Application May 10, 1939, Serial No. 84,909

Term of patent 14 years

To all whom it may concern:

Be it known that I, George W. Kohlmeyer, a citizen of the United States, residing at Buffalo, in the county of Erie and State of New York, have invented a new, original, and ornamental Design for a Lavatory, of which the following is a specification, reference being had to the accompanying drawing, forming part thereof.

In the accompanying drawing:

Fig. 1 is a perspective view of the lavatory showing my design.

Fig. 2 is a top plan view thereof.

Fig. 3 is a front elevation of the same.

Fig. 4 is a side view thereof.

Fig. 5 is a rear elevation of the same.

I claim:

The ornamental design for a lavatory, as shown and described.

GEORGE W. KOHLMAYER.
